APPARATUS FOR TURNING OVER THE WORK IN ROLL TRAINS

Filed May 26, 1925

2 Sheets-Sheet 1

The drawing shows a mechanical assembly with various components labeled with numbers. A horizontal line labeled 'X-X' extends through the center of the assembly. A vertical line labeled 'y' is perpendicular to the 'X-X' line. The assembly includes a base with two circular features labeled '1'. A horizontal plate labeled '2' is positioned above the base. A vertical frame structure is supported by the base. Inside the frame, there are two vertical columns. The left column contains a gear assembly with gears labeled '23', '24', '25', '5', '15', '16', '7', and '8'. The right column contains a vertical shaft with a gear labeled '10'. A horizontal rod labeled '13' is connected to the right side of the frame. A small rectangular component labeled '14' is attached to the right end of the rod. A label 'P' with a double-headed arrow is located on the left side of the base, indicating a force application point.

UNITED STATES PATENT OFFICE

HERMANN HOLTUS, OF ESSEN, GERMANY, ASSIGNOR TO "PHOENIX" AKTIEN-GESELLSCHAFT FÜR BERGBAU UND HÜTTENBETRIEB ABTEILUNG RUHRORT, DUISBURG-RUHRORT, OF DUISBURG-RUHRORT, GERMANY, A CORPORATION OF GERMANY

APPARATUS FOR TURNING OVER THE WORK IN ROLL TRAINS

Application filed May 26, 1925, Serial No. 32,930, and in Germany May 28, 1924.

This invention relates to devices for turning ingots and the like in rolling-mills, comprising a plunger with a tapering head which moves lengthwise in the direction of tilting and grips the ingot between itself and an abutment. When the plunger is thrust forward against an ingot lying on the roller track of the rolling-mill, it is intended to carry with it the side of the ingot remote 5 from the abutment, a certain grip being exerted owing to the space between the plunger and the abutment diminishing.

In some devices of this kind, the abutment is a counteracting plunger with a tapering 15 head. These devices have the disadvantage that they can only be used for tilting billets of particular cross-sections, more particularly of elongated cross-section, since both plungers move in guides that cannot shift 20 laterally, and so the space between the gripping surfaces must continually decrease as the plungers are thrust forward. As a consequence of this, for many cross-sections of billet the gripping pressure becomes so great 25 after a small angle of tilt that the billet is jammed between the plunger and abutment. It has, it is true, been proposed to mitigate this defect, for instance for billets of rectangular cross-section, by allowing a certain 30 amount of play between the plunger and its guide so that when the billet takes a diagonal position the head of the plunger can yield laterally. But this only provides for 35 tilting rectangular billets of certain dimensions depending on the play allowed.

The present invention provides for turning ingots, billets or the like of any cross-section through any desired angle; according 40 to it, the abutment or the plunger is held yieldingly under load by a gripping force exerted, for instance, by a weight or by a spring. The pressure requisite for gripping the billet is thus produced not by the diminution of the space between plunger and abutment but in the main by the gripping force. If, therefore, as the billet tilts, the pressure 45 of grip tends to become so great that the billet might jam, the space between plunger and abutment is automatically increased as 50 called for by the increasing horizontal di-

mension of the billet as it tilts. The gripping force is overcome by the jamming pressure and the abutment or the plunger yields laterally. So it is impossible for a billet of any cross-section to become jammed, and any 55 indenting of the billet that may occur where it is gripped is so small that it will be rolled out.

If the surface of the abutment bearing on the billet is vertical, the billet may possibly 60 shift along the abutment when the plunger advances to tilt it. This may be prevented by inclining the working surface of the abutment to the vertical and towards the plunger. The pressure of the abutment then has al- 65 ways a vertical downwardly directed component.

When the rolls have gripped the billet, the parts of the turning device which project above the roller track must be withdrawn below it, so that they are not exposed to the 70 blows of the tail end of the billet and do not hinder the supervision nor diminish the accessibility of the rollers. For this purpose, according to the invention, the plunger and 75 abutment are mounted on the slide running cross-wise of the billet beneath the roller track, in such a manner that they can be raised and lowered. The abutment can be readily and quickly presented against the bil- 80 let to be turned, and the tilting plunger then thrust upward.

To enable one turning device to be used for tilting in either direction, two plungers are employed having tapered heads and each 85 capable of being raised and lowered; according to the direction tilting, the one of them is thrust upward for tilting while the other yieldingly held plunger serves as the abutment. It is advantageous to pivot one 90 plunger about an axis parallel with the billet.

To prevent undesired shift of the billet along the abutment, it has already been proposed to make the abutment saw-like. In said known tilting devices, tilting is effected by 95 two toothed cheeks approached together, their teeth being oppositely directed.

According to the invention, the teeth of both plunger heads are directed towards the roller track, since each plunger may serve as 100

the abutment, and either one may be thrust forward in the same direction according to the desired direction of tilt.

It would be more difficult to control the turning device, if turning took place at different speeds for different cross-sections of billet. This may be avoided according to the invention, by giving the tapered head of the plunger a paraboloidal or ellipsoidal form. The stroke of the plunger for a given angle of tilt is then the same for billets of large or small cross-sections, and the plunger traverses the same working path.

Various forms of construction of the turning device are illustrated by way of example in the accompanying drawing:

Fig. 1 is a diagrammatical partial longitudinal section through one preferred form of construction,

Fig. 2 shows a modification of the plunger heads on a larger scale,

Fig. 3 shows the same modification used for tilting in the opposite direction, and

Fig. 4 shows another construction of the adjacent faces of the heads illustrated in Figs. 2 and 3.

The plane of the roller track is indicated in the figures by the line X—X. Beneath the roller track a carriage 2 is mounted on fixed rollers 1 so as to be movable transversely to the billet as indicated by the arrow P. Two plungers 3, 4 are located side by side upon the carriage, longitudinally movable in guides 5, 6. The guide 6 of plunger 4 is secured in vertical position upon the carriage 2 and a shaft 9 bears a toothed wheel 7 engaging in a rack 8 upon the plunger so that the plunger is movable vertically up and down. The guide 5 of plunger 3 is revoluble upon a shaft 23 mounted in a fixed bracket 21 of the carriage 2 parallel with the billet to be turned. Upon the shaft 23 there is also a pinion 24 engaging a rack 25 in the plunger 3 to move it up and down. A rod 10 is pivotally connected with the upper part of the guide 5 and at its other end to the short arm 11 of a bell-crank lever which rotates upon a pivot 12 on the guide 6 and carries on its longer arm 13 a weight 14 by which the plunger 3 is pulled toward the plunger 4. The plungers 3 and 4 are kept a certain minimum distance apart by adjacent stops 15, 16 thereon.

The heads 17, 18 of the plungers 3, 4 are formed as rollers revoluble about axially projecting pivot bolts 26, 26' of the plungers. The heads of both plungers taper towards the top, the head 18, however, having a curved taper while the head 17 is an ordinary truncated cone.

Prior to the tilting of the billet 19 lying on the roller track, which billet is shown by way of example as having a rhomboidal cross section, the head 17 of plunger 3 is in the position shown in dot-and-dash lines in Fig. 1 while the head 18 of plunger 4 is in

the position shown in full lines in said figure; that is to say, both heads are below the roller track. If the billet 19 is to be turned in the direction of the arrow Y, Fig. 2, plunger 3 is raised by mechanism (not illustrated) serving to rotate the pinion 24 until it projects above the roller track X—X, and the carriage 2 is then moved transversely until the head 17 contacts with the billet. The plunger 4 is now also raised until its head engages the billet 19 as indicated in full lines in Fig. 2. As the plunger 4 is raised further the billet 19 turns into the intermediate position shown in dotted lines in Fig. 2 in which it is gripped between the heads 17 and 18, the head 17 serving as the abutment. If the billet 19 has to be turned into the upright position indicated in dot-and-dash lines in Fig. 2, it would be indented on the further raising of plunger 4 unless plunger 3 were movable transversely to the roller track. Since, however, in accordance with the invention, the head 17 is held against the billet 19 with a regulable pressure determined by the weight 14, it can yield, and does yield, when the further raising of the plunger 4 increases the gripping pressure to such an extent that crushing of the billet might occur. It thus comes into the position shown in dot-and-dash lines in Fig. 2, the plunger 3 rotating about its shaft 23.

Thus, the distance between the two heads 17, 18 diminishes until the gripping pressure has reached a predetermined amount, whereupon the distance is automatically again increased so that indentation of the billet at the point where it is gripped is avoided or at any rate is so small only that it will certainly disappear in further rolling. Billets of any cross-sections whatever may be tilted with the aid of the improved turning device through any angle without damage to the billet.

When the desired tilting is completed, the grip upon the billet is so far slackened by slight withdrawal of the plunger 4 that the billet can be carried forward by the roller track, the heads 17, 18 guiding the billet in its tilted position.

When the rolls have gripped the billet, both plungers 3, 4 are withdrawn by means of the pinions 7, 24 until they lie beneath the plane X—X. Their heads 17, 18 are then not exposed to the blows of the tail end of the billet 19 and also they do not interfere with the supervision or accessibility of the rolls.

If the billet 19 rests upon the roller track in the position shown in Fig. 3, it may be tilted in the direction of the arrow Z by means of the plunger 3, the plunger 4 then serving as the abutment.

If the head 17 of plunger 3 is advanced until it contacts with the billet 19, further advance tilts the billet since the distance between the surfaces of the heads 17, 18 de-

creases until in the position shown in dotted lines the gripping pressure is so great that on further advance of the head 17 it overcomes the pressure exerted by the weight 14. The head 17 then yields so as to permit tilting of the billet without damage into the position illustrated in dot-and-dash lines in Fig. 3.

The part of the surface of the truncated conical head 17 which contacts with the billet 19, may be perpendicular to the roller track as shown in Fig. 1, that is to say, it may be vertical. But if the friction between the head and the billet is too small, the billet may possibly be lifted from the roller track which is not desired. In the construction shown in Fig. 2, this possibility is obviated by placing the head 17 at such an angle to the vertical that when tilting the part of its surface contacting with the billet is inclined to the vertical and towards the plunger 4, say for example by an angle α . When the plunger 18 is advanced, the counter-pressure on the billet 19 has then a downward component which prevents the billet lifting.

Lifting of the billet may also be prevented as indicated in Fig. 4 by making the surface of the heads 17, 18 toothed, the points of the teeth 20 being directed downward and so acting to restrain the billet from upward movement.

The heads 17, 18 of the plungers 3, 4 may alternatively be fast upon the plungers.

If the head 18 of plunger 4 is made paraboloidal or ellipsoidal in form, the stroke of the plunger is substantially the same for the same angle of tilt whether the billet be of large or small cross-section, so that the plunger describes the same working path. This materially simplifies control of the device.

What I claim, is:—

1. In a device for tilting ingots or the like work-pieces, the combination with two plungers having tapered heads between which the work-piece is gripped, either of said plungers serving as an abutment, of means consisting of a weighted lever operatively attached to one of said plungers for yieldingly holding it up to its work by a gripping force acting transversely to the work-piece.

2. A construction as specified in claim 1, in which the surface of the abutment plunger acting upon the work-piece is inclined to the vertical and towards the other plunger.

3. In a construction as specified in claim 1, a carriage transversely movable to the work-piece and upon which said plungers are mounted in up and down movable fashion.

4. In a construction as specified in claim 1, means for advancing one or the other of said plungers for tilting according to the direction of tilt.

5. In a construction as specified in claim 1, a shaft parallel with the work-piece and about which the yieldingly held plunger is rotatable.

6. A construction as specified in claim 1, in which the tapered plunger heads are toothed, the teeth of both plunger heads being directed downwards.

7. A construction as specified in claim 1, in which the tapered head of one plunger has a curved taper while that of the other plunger forms a truncated cone.

8. A construction as specified in claim 1, in which the tapered heads of said plungers are axially rotatable thereon.

In testimony whereof I hereunto affix my signature.

HERMANN HOLTUS.
